US00D716760S

(12) **United States Design Patent**
Brunner et al.

(10) **Patent No.:** **US D716,760 S**
(45) **Date of Patent:** **** Nov. 4, 2014**

(54) **GAMING HEADSET**

(71) Applicant: **Beats Electronics, LLC**, Santa Monica, CA (US)

(72) Inventors: **Robert D. Brunner**, San Francisco, CA (US); **Christopher Kuh**, San Francisco, CA (US)

(73) Assignee: **Beats Electronics, LLC**, Culver City, CA (US)

(**) Term: **14 Years**

(21) Appl. No.: **29/464,539**

(22) Filed: **Aug. 18, 2013**

Related U.S. Application Data

(60) Division of application No. 29/426,082, filed on Jun. 29, 2012, now Pat. No. Des. 691,112, which is a continuation-in-part of application No. 29/410,585, filed on Jan. 9, 2012.

(57) **CLAIM**

The ornamental design for gaming headset, as shown and described.

DESCRIPTION

FIG. 1 is a perspective view of a gaming headset showing our new design, the front face of the opposite ear cup is a mirror image;

FIG. 2 is a back view of the embodiment of the gaming headset shown in FIG. 8;

FIG. 3 is a bottom view of the embodiment of the gaming headset shown in FIG. 8;

FIG. 4 is a front view of the embodiment of the gaming headset shown in FIG. 8;

FIG. 5 is a left side view of the embodiment of the gaming headset shown in FIG. 8;

FIG. 6 is a right side view of the embodiment of the gaming headset shown in FIG. 8; and,

FIG. 7 is a top view of the embodiment of the gaming headset shown in FIG. 8.

1 Claim, 7 Drawing Sheets
